UNITED STATES PATENT OFFICE.

CLAUDE L. POST, OF CHICAGO, ILLINOIS.

CLAMPING MEANS FOR PRINTING SLUGS AND THE LIKE.

Application filed October 3, 1924. Serial No. 741,427.

My invention relates to improvements in clamping means and more particularly to means adapted to removably secure one or more printing slugs or blocks upon a type 5 roll or the like, the same being adapted for use in envelope handling and printing devices. My invention has among its objects the production of a device of the kind described which is simple, durable, reliable, 10 efficient, compact and satisfactory for use wherever found applicable. It has particularly as an object the production of an adjustable clamping means for securing type, particularly printing slugs or the like, to the type roll which permits the slugs being 15 adjusted on the roll, and is adapted for rolls of various types of presses. I have particularly shown the same as applied to my improved press. The same also includes 20 means cutting the slugs so that they are uniform and fit the roll and clamping means. Many other objects and advantages of the construction herein shown and described will be obvious to those skilled in the art 25 from the disclosures herein given.

To this end my invention consists in the novel construction, arrangement and combination of parts herein shown and described, and more particularly pointed out 30 in the claims.

In the drawings, wherein like reference characters indicate like or corresponding parts:

Fig. 1 is a sectional view through a printing machine, embodying the improvements herein set forth;

Fig. 2 is a plan view of the roll;

Fig. 3 is an end elevation of the same;

Fig. 4 is a section taken substantially on line 4-4 of Fig. 3;

Fig. 5 is a section taken substantially on line 5-5 of Fig. 3;

Fig. 6 is a perspective view of the spacer 8;

Fig. 7 is a view similar to Fig. 4, illustrating a modified arrangement; and

Fig. 8 is a sectional view taken substantially on line 8-8 of Fig. 7.

In the drawings, wherein I have illustrated the preferred embodiment of my invention, 1 represents a portion of the printing mechanism frame, a complete press not being shown, and 3 represents the type roll with which is associated the feed or impression roll 4, it being understood that the 55 parts are driven in any suitable manner, one type of driving mechanism being herein-

after described briefly. The impression roll 4 is shown provided with a tympan 2 secured thereon and a feeding arc 2' arranged to cooperate with the type roll, as shown 60 in Fig. 1. The envelopes or other matter to be printed are delivered between the rolls 3 and 4 in any suitable manner, not necessary to describe herein.

The particular type roll shown is arranged 65 to secure and carry one or more linotype slugs 5, having the usual character 6 thereon for printing purposes, the slugs being produced in the usual manner, not necessary to describe herein. As shown the roll 3 has 70 a groove 7 therein, the depth of the groove being such that when the slugs rest on the bottom 7' the face 6 will be in proper printing position to cooperate with the roll 4. As shown, the faces of the slugs 5 are parallel, and to maintain the same in proper 75 relation to the groove I provide wedge-shaped spacers 8, which, when they are inserted, properly space and retain the slugs in printing position. The two end or side 80 spacers 9 I prefer to make with parallel sides, although printing slugs, when required, may be employed in place of either one of the spacers 9. Arranged over the slugs is a plate or frame 10 having an opening 11 through the same, through which the printing faces 6 of the slugs project, the plate being of such thickness that it does not project to or beyond the face of the slugs. As shown, the slugs are provided with a 90 shoulder portion 13-14, this being cut so that the slugs fit the frame and so that the frame may fit close on the roll face.

Referring to Fig. 4, it will be noted that the frame is preferably beveled at the edges 95 or ends, as indicated at 12. At either side of the type groove 7 is provided a wedge-shaped slot 15 in each of which I arrange wedge-shaped members 16. These wedge-shaped members are mounted on a rod 17 which is 100 preferably threaded in opposite directions as indicated at 18 and 19, so that when the rod is turned it will move the wedges 16 together or apart, as the case may be. Generally I prefer to form the rod at the end 105 20 so that it may be gripped by a wrench or the equivalent. The members 16 are provided with projecting parts 21 formed with inclined faces 22 arranged to engage with the beveled edges or ends 12 of the frame or 110 clamping plate 10.

The mechanism may be driven in any suit-

- able manner, as, for example, by a motor 26 operatively connected with the drive shaft 25, which is arranged to transmit power from the motor to a drive wheel 29 co-
 5 operating with the drive member 30. To facilitate cutting the shoulders 13 and 14 on the slugs, I prefer to provide a saw 27 and table 28, the saw being driven from the shaft 25 or in an equivalent manner.
 10 I have shown in Figs. 7 and 8 a modified clamping means which engages the slugs similar to the plate 10 and retains them firmly in place, the same being substantially a skeleton frame. Referring to these figures, 5 represents the slugs provided with the printing faces 6. The slot 7 is similar to that previously described, as are also the wedges 8. I have likewise shown the slots 15. In this case the slugs 5 are shown
 15 with the shoulders 31 arranged at the ends of the slugs. At the shoulders 31 are rings 32 provided with ends 33 adapted to engage in the slots 15 and be firmly held therein. These clamping members 32 are made
 20 so as to fit substantially closely to the plate or slugs and be retained in place by the engagement with the undercut sides of the slots. They may be slipped on or off over the end of the roll.
 25 30 It will be seen from the preceding that the rotation of the threaded bars 17 will move the clamping members 16 to tightly engage the plate and secure it together with the type slugs in place. Likewise with the
 35 rings 32 or segments, they will serve as a combined clamping member and roll engaging means.
 The centering of the type on the roll may be as desired, the construction permitting
 40 adjustment on the type roll from one end to the other, and the device is applicable for accommodating one or more slugs. If only one slug is employed or desired, additional blank slugs or spacers 9 may be
 45 employed, or wedges of sufficient width, to give the results. The type roll shown is applicable for slugs or plates.
 Having thus described my invention, it is obvious that various immaterial modifications
 50 may be made in the same without departing from the spirit of my invention; hence I do not wish to be understood as limiting myself to the exact form, construction, arrangement and combination of parts
 55 herein shown and described or uses mentioned.
 What I claim as new and desire to secure by Letters Patent is:
1. In a printing press, a type roll having
 60 a longitudinal groove therein and a longitudinal slot at each side of said groove, and means for securing type in said groove consisting of means for engaging the ends of a type slug positioned in said groove,
 65 and means cooperating with the said slots

at either side thereof for maintaining said retaining means in place, said maintaining means being adjustable longitudinally of the slots.

2. In a printing press, a type roll having 70 a longitudinal groove formed therein with the walls extending radially and a longitudinal slot at each side of said groove, and adjustable means for securing type in said groove consisting of means for engaging 75 the ends of a type slug in said groove, and means engageable in said slots at either side thereof for detachably maintaining said retaining means in place.

3. In a printing press, a type roll having 80 a longitudinal type groove therein formed with the walls extending radially and with a longitudinal slot at either side thereof, wedge-shaped means in said type groove for maintaining a type slug in printing position 85 within said groove, a plate removably arranged over said type slug and engaging adjacent the ends thereof and having an opening for the projection of the printing face of the type therethrough, and adjustable means in said slots for securing said clamping plate in place.

4. In a printing press of the kind described and in combination, a type roll provided with a type receiving groove extending longitudinally thereof, and with a longitudinal slot at either side of the groove, a clamping plate arranged over said slugs and engaging the ends thereof, said plate having an opening therethrough and of a thickness 95 to lie below the face of the type projecting through said opening, and adjustable means for securing said plate at said slots.

5. In a printing press of the kind described and in combination, a type roll provided with a type receiving groove extending longitudinally thereof, means for spacing the type in said groove, said roll having a slot at either side of the groove, a clamping plate arranged over said slugs 105 and engaging the same, said plate having an opening therethrough and being of a thickness whereby the top face will lie below the face of the type projecting through said opening, and means adjustably arranged in said slots and engaging the side walls thereof for securing said plate in place.

6. The combination with a type roll having a longitudinal type groove formed therein of greater width than the type and having longitudinal slots formed therein spaced from said groove, of wedge-shaped means disposed in said groove for maintaining the type in printing position, and means adjustably engaging the slots for preventing radial displacement of the type relative to the roll.

7. The combination with a type roll having a longitudinal type groove therein with radially extending walls, said roll having 130

longitudinal slots formed therein spaced from said groove, of means in said groove engaging said walls for maintaining the type in printing position, and means adjustably engaging said slots for preventing radial displacement of the type relative to the roll. 15

8. In combination, a type roll of rigid construction having a longitudinal groove therein, and adjustable mechanism for inserting type in said groove, said mechanism comprising means extending circumferentially of said roll over and beyond the type, and means engageable with the roll at points 10

spaced from the slot for securing said first- 15 mentioned means in an adjusted position with respect to the roll.

9. In combination, a type roll of rigid construction having a longitudinal groove therein, an apertured arcuate plate extending circumferentially of said roll over and beyond the type, and means engageable with the roll at points spaced from said groove for securing said plate in an adjusted position with respect to the roll. 20

In testimony whereof, I have hereunto signed my name. 25

CLAUDE L. POST.
